UNITED STATES PATENT OFFICE.

EDWIN CARLSON, OF MINNEAPOLIS, MINNESOTA, ASSIGNOR OF ONE-HALF TO CARL M. E. CARLSON, OF MINNEAPOLIS, MINNESOTA.

SLIDING-DOOR FASTENER.

No. 901,419.

Specification of Letters Patent.

Patented Oct. 20, 1908.

Application filed July 27, 1907. Serial No. 385,871.

To all whom it may concern:

Be it known that I, EDWIN CARLSON, a citizen of the United States, residing at Minneapolis, in the county of Hennepin and 5 State of Minnesota, have invented certain new and useful Improvements in Sliding-Door Fasteners; and I do hereby declare the following to be a full, clear, and exact description of the invention, such as will enable others skilled in the art to which it 10 appertains to make and use the same.

My invention has for its object to provide an improved sliding door fastener especially adapted for use on grain doors for 15 box cars; and to this end, it consists of the novel devices and combinations of devices hereinafter described and defined in the claims.

In the accompanying drawings, which 20 illustrate the invention, like characters indicate like parts throughout the several views.

Referring to the drawings; Figure 1 is a 25 view in front elevation, showing the central portion of the body of a box car and a grain door applied thereto, with my improved sliding door fastener secured to the grain door. Fig. 2 is a horizontal section taken on the line $x^2 x^2$ of Fig. 1; and Fig. 3 is a 30 view corresponding to Fig. 1, but showing the lock in a released position.

The numeral 1 indicates a portion of the body of an ordinary box car, the same having in its sides the usual door opening 2, to 35 which door opening a grain door 3 is applied. The grain door 3 may be of the ordinary or any desired construction, and mounted to slide vertically by any suitable means, not shown.

40 The improved fastener consists of a lever 4 hinged to the grain door 3, and a lock bolt 5 hinged to the inside and to the intermediate portion of said lever 4 and having its lower or free end formed with an out-turned hook 6. A lock plate 7 secured to the floor 45 of the box car 1 is adapted to receive the free or hooked end 6 of the lock bolt 5. The floor of the box car 1 is cut away at 7^a under said lock plate 7 to afford a clearance 50 for the free or hooked end 6 of the lever 4. The lock bolt 5, and that portion of the lever 4, between its hinge and the hinge of said lock bolt, forms a toggle lever which, when straightened out, forces the free or 55 hooked end 6 of the lock bolt 5 into the lock

seat 7, and holds the grain door so that it can not be moved edgewise away from said lock seat 7. To secure the lever 4 and the lock bolt 5 together, so that the hooked end 6 of the lever 4 will be secured within the 60 seat 7, a staple 8 is secured to the grain door near its lower edge, and arranged to project through alined slots 9 and 10 formed in said lever 4 and lock bolt 5. By passing a pin 11 through the projecting end of the staple 65 8, the lever 4 and the lock bolt 5 may be secured together.

If desired to further seal the car, a second car seal may be secured to the projecting end of the pin 11. To prevent the pin 11 70 from being lost, the same is secured to the lever 4 by a short chain 12.

As is evident, the lever 4 and the lock bolt 5, hold the grain door against lateral movements, prevent the same from working 75 upward under the continued movement of the car, and also prevent the door from being opened without first breaking the car seal.

While I have shown my improved sliding 80 door fastener applied to a grain door, for the purpose of illustration, the same may be applied to any sliding door mounted for either vertical or horizontal movements.

What I claim is:—

1. The combination with a door and a frame, the latter having a lock seat adjacent to one edge of the door, of a lever hinged to said door, a lock bolt hinged to the intermediate portion of said lever and adapted to interlock with said lock seat when said lever and bolt are folded together, and means for locking said lever and lock bolt together when in their folded position, substantially as described. 95

2. The combination with a door and a frame, the latter having a lock seat adjacent to one edge of the door, of a lever hinged to said door, a lock bolt hinged to the intermediate portion of said lever and having a 100 hooked end adapted to interlock with said lock seat against endwise removal, when said lever and lock bolt are folded together, and means for locking said lever and lock bolt together when in their folded position, substantially as described. 105

3. The combination with a door and a frame, the latter having a lock seat adjacent to one edge of the door, of a lever hinged to said door, a lock bolt hinged to the inter- 110

- mediate portion of said lever, and having a hooked end adapted to interlock with said lock seat against endwise removal, when said lever and lock bolt are folded together,
5 alined slots formed in said lever and lock bolt, and a staple secured to said door and arranged to project through said alined slots when the said lever and lock bolt are folded together, substantially as described.
10 4. The combination with a door and a frame, the latter having a lock seat adjacent to one edge of the door, of a lever hinged to said door, the lock bolt hinged to the intermediate portion of said lever and having a
15 hooked end adapted to interlock with said

lock seat against endwise removal when said lever and lock bolt are folded together, alined slots formed in said lever and lock bolt, a staple secured to said door and arranged to project through said alined slots 20 when the said lever and lock bolt are folded together, and means for locking said lever and lock bolt to said staple, substantially as described.

In testimony whereof I affix my signature 25
in presence of two witnesses.

EDWIN CARLSON.
